Primary Examiner — Ricky Pham

(74) *Attorney, Agent, or Firm* — Price Heneveld LLP

(57) **CLAIM**

The ornamental design for a cooking appliance as shown and described.

DESCRIPTION

FIG. 1 is a top perspective view of a cooking appliance according to the design in a first configuration;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a bottom perspective view thereof;

FIG. 9 is a top perspective view of the cooking appliance according to the design in a second configuration;

FIG. 10 is a front elevation view thereof;

FIG. 11 is a back elevation view thereof;

FIG. 12 is a right side elevation view thereof;

FIG. 13 is a left side elevation view thereof;

FIG. 14 is a top plan view thereof;

FIG. 15 is a bottom plan view thereof; and,

FIG. 16 is a bottom perspective view thereof.

The portions of the article shown in even broken line form no part of the design.

Dash-dot-dash broken lines adjacent un-shaded areas represent bounds of the claimed design and form no part of the design themselves.

1 Claim, 14 Drawing Sheets
